ADOLPH W. LISSAUER AND JULIUS CREDO, OF LOUISVILLE, KENTUCKY, ASSIGNEES
TO LOUISVILLE DRYING MACHINERY CO. INC., OF LOUISVILLE, KENTUCKY, A COR-
PORATION OF KENTUCKY.

ROTARY COOLER.

Application filed February 2, 1926. Serial No. 85,528.

- Our invention relates to a rotary cooler which is practically dust-tight and which has a large cooling surface for a comparatively small over-all dimension.
- 5 Another object of the invention is to provide a cooler which can be used for substances that are apt to form explosive mixtures with an excess of air.
- In the appended drawing, Figure 1 is a 10 longitudinal section on a line 1—1, Figure 2. Figure 2 is an end elevation of the charge receiving end of the cooler, and
- 15 Figure 3 is a transverse section on line 3—3, Figure 1, illustrating the discharge end of the cooler.
- Referring to the drawings, 5 is a cylindrical drum provided at each end with a head 6. Each of the heads has an annular chamber 7, united by tubes 8 which extend 20 through the drum in proximity of its inner periphery and through which tubes the two chambers are in communication. These tubes therefore form an annular row within the drum.
- 25 Each of the heads has a transverse conduit 9 which is depressed from the plane of the head into the drum so as to afford more room at the heads. In addition, by depressing the conduits 9, the same are rendered more flexible to provide the necessary play required 30 for changes in temperature. Each of the conduits 9 has a pipe 10 projecting through the axis of the corresponding head and leading out of the drum. Each of the pipes 10 is provided with a stuffing box 11, which couples the pipe 10 to a pipe 12, the pipes 12 being stationary.
- The head 6 at the charging end of the drum has a stationary housing 13 on which 40 it is revolvably mounted. This housing is provided with a feeding hopper 14, same being in dotted and dash line in Figure 1, through which the material to be dried is continually fed. A manhole 14' is also provided in the housing 13. The charging head 6 also carries feeder blades 15 which force the material passing through the hopper away from the head 6.
- The head 6 at the discharge end of the 45 cooler is provided with a series of spiral blades 16 so arranged that the material falling thereunto is carried by the blades on a cone 17. This cone 17 is disposed coaxial- ly with the discharge head and is pointing outwardly. The discharge head 6 is also provided with a flaring out opening 18 into which the cone enters and from where the material is delivered by the cooler.
- The drum 5 is mounted on rollers 19 so that there is a pitch from the inlet to the outlet end of the cooler. A gear 20 is secured to the drum and to which motion is imparted by a pinion 21 connected to a drive shaft 22. Longitudinal motion of the 50 dryer is prevented by rollers 23.
- The material entering the cooler through the hopper 14 is tossed along on and from the tubes 8 in its movement from the inlet to the outlet end. Through the tubes 8, a cooling fluid, such as water, is circulated, the 55 fluid entering the tube 12 at the discharge end of the cooler and leaving the tube 12 at the inlet end of the same. In other words, the direction of the cooling medium and the material to be cooled are in opposite directions.
- This type of cooler is particularly suitable 60 for drying materials of the type which are apt to form explosive mixtures with an excess of air. As an example, charcoal may be cited, for in this type of cooler no air is used for cooling, and very little of same can enter, due to the fact that material is continually charged through the cooler and the inlet and outlet heads have restricted 65 openings. Furthermore, by providing an annular series of tubes 8 in the periphery of the drum a very large cooling surface is provided for a comparatively small over-all dimension of the cooler, thereby forming a 70 cooler of high capacity.
- We claim
1. In a revoluble cooler a revoluble discharge head having an outwardly flaring opening coaxial with the head, a cone at the 75 opening pointing thereto and revoluble with the head, a plurality of spiral blades revoluble with the head for directing the material on to the cooler and a supply pipe for a cooling medium passing through said opening and cone into said head.
2. In a revoluble cooler a drum mounted 80 to revolve and having an inlet and a discharge head revoluble therewith, each of said heads having an annular chamber, tubes 85 extending within the drum and connecting

the annular chambers of the heads, pipes
from each of the annular heads disposed
transversely of the drum and depressed into
the drum from each of the heads, an axial
5 pipe to each of the transverse pipes extend-
ing through the adjacent head and out of
same, stationary means closing the inlet head,
a hopper associated with said means for feed-
ing material into the drum, the discharge

head having an outwardly flaring axial open- 10
ing, a cone carried by the head and point-
ing toward the opening, and a series of spiral
blades associated with the discharge end of
the drum for leading the material on to the
cone and out of the axial opening.

ADOLPH W. LISSAUER.
JULIUS CREDO.
